METAL TRUSSLESS ROOF

John F. Blaski, Chicago, Ill.

Application December 5, 1940, Serial No. 368,563

10 Claims. (CL. 108—1)

My invention relates to sheet metal roof constructions of the type which are arched between opposing side supports, and it is an object of my invention to provide an improved roof construction of this type which is trussless and requires no supports, other than the supports on which it rests, either inside or outside the roof for sustaining it.

It is also an object of my invention to provide an improved roof construction of this type which is constructed of channeled roof members of thin sheet material but which will be strong, rigid and capable of withstanding large snow and wind loads thereon without appreciable sagging even when the roof is large and the distance between the side supports therefor is great.

Another object of my invention is to provide a roof construction of this type adapted to be readily heat insulated to prevent heat from passing therethrough.

A further object of my invention is to provide an improved roof construction of this type comprising a plurality of cooperative roof members which upon being erected in place produce a roof which is substantially watertight.

It is still another object of my invention to provide a roof construction of this type in which the individual members may be quickly and easily assembled and just as quickly and easily dismantled, if desired.

In its preferred form, my improved roof construction comprises a plurality of channeled sheet metal roof members which are fastened together in end to end relation in courses extending from one edge of the roof to the opposite edge thereof with the members of each course fastened at their sides to the sides of the members of adjacent courses, and it is another object of my invention to provide guide means on one side of the individual members whereby the members of a course in construction may be quickly and easily positioned and held correctly with respect to the previously installed member of that course and with respect to the members of the previously erected course adjacent thereto, all preparatory to and while the fastening elements are being inserted.

The invention consists of the novel constructions, arrangements and devices to be herein-after described and claimed for carrying out the above stated objects and such other objects as will appear from the following description of certain preferred embodiments illustrated in the accompanying drawings, wherein—

Fig. 1 is an end elevational view of a roof construction embodying the principles of my invention;

Fig. 2 is a plan view of a portion thereof without insulation;

Fig. 3 is a plan view of a portion thereof on an

enlarged scale taken substantially from line 3—3 of Fig. 1 with part of the insulation removed;

Fig. 4 is a sectional view thereof, on a further enlarged scale, taken on line 4—4 of Fig. 3;

Figs. 5 and 6 are sectional views thereof taken on lines 5—5 and 6—6, respectively, of Fig. 3;

Fig. 7 is a sectional view similar to Fig. 4 showing a modification of my invention;

Fig. 8 is a plan view of a fragmentary portion 10 of a construction showing another modification of my invention;

Fig. 9 is a sectional view taken on line 9—9 of Fig. 8;

Fig. 10 is a sectional view on an enlarged scale 15 of the constructions shown in Figs. 8 and 9; and

Fig. 11 is a perspective view of a roof member used in the constructions illustrated in Figs. 1—6.

Like characters of reference designate like 20 parts in the several views.

Referring to Figs. 1—6 and 11, it will be noted that the roof construction is in the form of an arch which extends between and upwardly toward its center from opposite side supports 15 and 16. The roof is formed by a plurality of 25 courses, for example courses 17, 18 and 19 shown in Fig. 2, which extend side by side between the supports 15 and 16. Each of the courses forming the roof construction comprises a plurality 30 of roof members 20.

The roof members 20 are formed from sheet 35 metal, say 14 gauge, galvanized or otherwise treated to resist rust. Each member is bent along longitudinal lines thereof (see Figs. 4 and 11) into channel-like shape with a central web 20a and generally vertically extending flange means on opposite sides thereof. The flange means 40 comprises an obliquely extending flange 20b, an outwardly extending flange 20c, and a flange 20d which extends vertically at substantially right angles to the web 20a. The flange 20d on one side of each of the members is formed with a return bend 20e. The web and side flanges adjacent the ends of each member are provided with 45 openings 21. The side flanges 20d along their lengths are provided with openings 22.

The channeled members 20 are disposed together in end to end relation into courses, and 50 preferably with the webs 20a and all the flanges 20b, 20c and 20d of adjacent members of each course in lapping engagement, and with the return bends 20e of the members in each course all positioned on the same side of the course. Adjacent members of each course are prefer-

ably positioned such that the member nearer the center of the roof overlaps an adjacent lower member, so that any water on the members will flow over the lapped joints of the members. The members preferably are disposed with their flange means comprising flanges 20b, 20c, and 55 20d extending outwardly of the roof or with

the open side of each channeled member facing outwardly, and with the openings at the respective ends of each member in registry with the end openings of adjacent members. Bolts 23 pass through the registered end openings of adjacent members in each course and hold the members together. The members in each of the courses are positioned with their flanges 20d, having the return bend 20e formed thereon, in lapping or face to face engagement with the plain flanges 20d (those not formed with a return bend) of members of an adjacent course, and preferably with the return bends 20e of the members overlapping the upper edges of the adjacent plain flanges 20d. The members in each course are positioned such that the joints therebetween are staggered or non-coincident with the joints between the members of courses adjacent thereto, see Figs. 2 and 3. The openings 22 in the lapped side flanges 20d of members of adjacent courses are in registry, and bolts 24 pass through such registered openings and hold adjacent courses together. The return bends 20e overlapping the plain flanges 20d of members adjacent thereto at the side, act as additional means for holding adjacent courses together and function, similar to the lapped joints between the ends of the members of each course, to form a strong connection between adjacent members and a watertight joint between lapping flanges 20d.

The flanges 20c on opposite sides of the members form ledge means for supporting panels 25 of heat insulating material, or to which such panels may be secured. The panels insulate the roof as a whole and substantially reduce passage of heat through the roof. Bracing bars 26 are also positioned on opposite flanges 20c of each member and are fastened thereto, preferably by means of bolts. The bars 26 may be provided at the centers and also at the ends of the individual members. The bars 26 materially strengthen the roof.

My improved roof may be easily constructed by first building one course, preferably an end course, between the side supports 15 and 16. Then members of an adjacent course are positioned one by one and secured in place with their return bends 20e lapping the vertically extending plain flanges 20d of the members of the previously erected course, the joints between the members of the second course being staggered with respect to the joints between the members of the first course. The flanges 20d bolted together in face to face contact provide a continuous vertically extending rib at the meeting sides of adjacent courses extending from one end thereof to the other which results in a very strong construction. The bolt openings are so disposed in the flanges 20d and the return bends 20e on the members are so shaped that the bolt openings of the contacting flanges are easily brought into registry simply by positioning the members of the course in construction with their return bends contacting the edges of the plain flanges 20d of the members of the completed course. The arrangement is such also that when the openings of adjacent side flanges 20d are in registry, the openings 21 at the lapping end of the member being positioned are also in registry with the openings 21 of the adjacent member in the same course. The bolts may be passed easily through the registering openings, therefore, to fasten the member in place. The plain flange 20d preferably has its free edge arched

substantially the same as the arched contour of the roof at the member; the return bend 20e is preferably similarly arched. It will be apparent that the return bends 20e and the plain flanges 5 20d form effective cooperating guide means for properly positioning the members preparatory to insertion of the bolts.

The individual members 20 may be of any preferred size. I contemplate making them about 2 ft. in width and from about 4 ft. to about 10 ft. in length. The side flanges 20d of the members may have a uniform curvature at their free edges, and in such case the members may be alike, or formed from the same dies or bending apparatus, and in that case the completed roof will have a uniform curvature from one support to the opposite support. When the span between the supports is large, say 100 ft. or more, I prefer to use two or more types of members 20, each having the free edges of their respective side flanges 20d curved differently. For example, the members of the section A of the roof shown in Fig. 1 may be formed with side flanges 20d curved at their free edges on a relatively short radius, those members comprising the roof section B may be formed with the free edges of their side flanges 20d curved on a relatively longer radius, while the members comprising the roof section C may have side flanges 20d straight at their free edges. It will be obvious that roofs varying greatly in the spans between opposite supports may be erected readily from prefabricated stocks of members of the three types mentioned simply by lengthening or shortening one or more of the roof sections A, B and/or C, and using therefor the required number of the members having side flanges 20d of the proper form at their free edges. It will be understood also that the bolt openings in the side flanges 20d may be located slightly differently in one type of member as compared with those of another type. While in most cases the channeled members 20 probably will be placed with their open sides upward as shown, I wish it to be understood that they may be reversed and placed with their open sides downwardly.

The embodiment of my invention illustrated in Fig. 7 differs from the embodiment above described in that alternate courses thereof are formed of shallow roof members 27. Each roof member 27 comprises a web 27a and flange means on each side thereof. The flange means comprises on one side a flange 27d formed with a return bend 27e and on the other side a plain flange 27d with no return bend. The flanges 27d are similar to the flanges 20d, and the return bend 27e is similar to the return bend 20e. The members 27 in one course, therefore, fit with members 20 in another course in the same manner as the courses of members 20 fit together. A panel of insulation 25 may be positioned directly on the web 27a of each of the members 27 as shown. This embodiment of my invention is satisfactory when it is not necessary to have a roof of as great strength as the roof first described.

The roof construction illustrated in Figs. 8 and 9 is one particularly adapted for a building or a part of a building which decreases in width at one or both ends. The roof construction now to be described also decreases in height. The modified construction comprises building members 28 each of which comprises a web 28f, an obliquely extending flange 28b, a flange 28c, flanges 28d, and a return bend 28e. The parts 28b, 28c, 28d and 28e are similar to the respec-

tive parts 20b, 20c, 20d and 20e, and the members 28 fit together in the same manner as the members 28. Each of the roof members 28, unlike each of the members 20, is disposed lower or farther inward of the roof at one of its side edges than at the other, and a roof built with the members 28 positioned correspondingly in each course thus decreases in height and width, as shown.

My roof constructions may be easily erected because each individual channeled member is of light weight and easily handled. I prefer to use bolts for fastening the members together because they are more easily inserted in erecting a roof and, of course, may be easily removed should dismantling of the roof be desired. A roof that is dismantled, obviously, may be re-erected at another location if desired to cover the same or smaller area, or a larger area if the required additional members are supplied. The constructions, therefore, are flexible and readily lend themselves to considerable latitude in building operations.

My improved roof constructions, even when the individual channeled members are of light gauge metal, are exceedingly strong and capable of withstanding heavy snow and wind loads thereon. The individual members may be channeled in any preferred way and as deeply as desired to provide the requisite strength for any given construction. Each course of members spanning or extending over opposing supports is arched upwardly, and the course at each of its side edges is reinforced by its vertical side flanges which when bolted in cooperating relation with the side flanges of adjacent courses provide strong vertical reinforcing and load carrying ribs. If desired, the exterior surface of a completed roof may be coated with tar, asphalt or other suitable material, and such material may be applied directly to the sheet metal construction or to the panels of insulation material when the latter is used exteriorly of the roof. The constructions are well adapted for airplane hangars, large assembly halls, shop buildings, etc.

I do not intend to limit the invention to the details of construction shown and described except only insofar as certain of the appended claims may be specifically so limited, as it will be obvious that modifications may be made without departing from the principles of the invention.

I claim:

1. A trussless roof comprising in combination a plurality of courses extending from one edge to the opposite edge thereof, each course being arched lengthwise thereof upwardly from its ends towards its center and comprising a plurality of sheet metal channeled members, each of said members comprising side flange means connected by a web, said members of each course being disposed in end to end relation with at least portions of the ends of adjacent members in lapping engagement and with at least portions of their flange means in lapping engagement with at least portions of the flange means of the members of adjacent courses, the joints between the members of each course being non-coincident with the joints between the members of adjacent courses, fastening elements extending through the lapped end portions of adjacent members of each course, and fastening elements extending through said portions of the flange means of the members of one course at their respective sides and the side flange portions of the members of adjacent courses in lapping arrangement therewith.

2. A trussless roof comprising in combination

a plurality of courses extending from one edge to the opposite edge thereof, each course being arched lengthwise thereof upwardly from its ends towards its center and comprising a plurality of sheet metal channeled members, each of said members comprising side flange means connected by a web, said members of each course being disposed in end to end relation with the webs and the flange means of adjacent members in lapping engagement and with at least portions of their flange means in lapping engagement with at least portions of the flange means of the members of adjacent courses, the joints between the members of each course being non-coincident with the joints between the members of adjacent courses, fastening elements extending through the lapped webs and the lapped flange means of adjacent members of each course, and fastening elements extending through said portions of the flange means of the members of one course at their respective sides and the side flange portions of the members of adjacent courses in lapping arrangement therewith.

3. A trussless roof comprising in combination a plurality of courses extending from one edge to the opposite edge thereof, each course being arched lengthwise thereof upwardly from its ends towards its center and comprising a plurality of sheet metal channeled members, each of said members comprising side flange means connected by a web, said side flange means on opposite sides of each member comprising a first flange connected to said web and a second flange joined by connecting flange means with said first flange, said members of each course being disposed in end to end relation with the webs of adjacent members in lapping engagement, the joints between the members of each course being non-coincident with the joints between the members of adjacent courses, each of said members being disposed with its second flanges at its respective sides in lapping engagement with the second flanges of members of adjacent courses, fastening elements extending through the lapped webs of adjacent members of each course, and fastening elements extending through the lapped second flanges of members of adjacent courses.

4. A trussless roof comprising in combination a plurality of courses extending from one edge to the opposite edge thereof, each course being arched lengthwise thereof upwardly from its ends towards its center and comprising a plurality of sheet metal channeled members, each of said members comprising side flange means connected by a web, said members of each course being disposed in end to end relation with at least portions of the ends of adjacent members in lapping engagement, the joints between the members of each course being non-coincident with the joints between the members of adjacent courses, said flange means on each member including on each side thereof a vertically extending flange with the flange on one side terminating in a return bend, each of said members being disposed with its vertically extending flanges at its respective sides in lapping engagement with the vertically extending flanges of members of adjacent courses and with its return bend in lapping relation with the adjacent vertically extending flanges of members of an adjacent course, fastening elements extending through the lapped end portions of adjacent members of each course, and fastening elements extending through the lapped vertically extending flanges of members of adjacent courses, said return bend on each of said members and

the vertically extending flanges lapped thereby constituting guide means for the positioning of members of one course relative to an adjacent course.

5. A trussless roof comprising in combination a plurality of courses extending from one edge to the opposite edge thereof, each course being arched lengthwise thereof upwardly from its ends toward its center and comprising a plurality of sheet metal members, each of said members being channel-like in shape and comprising side flange means connected by a web and being positioned with its open side disposed outwardly of the roof, said members of each course being disposed in end to end relation with at least portions of the ends of adjacent members in lapping engagement, the joints between the members of each course being non-coincident with the joints between the members of adjacent courses, said flange means on each member including on each side thereof an upwardly extending flange with the flange on one side terminating in a return bend, each of said members being disposed with its upwardly extending flanges at its respective sides in lapping engagement with the upwardly extending flanges of members of adjacent courses and with its return bend in overlapping relation with the adjacent upwardly extending flanges of members of an adjacent course, fastening elements extending through the lapped end portions of adjacent members of each course, and fastening elements extending through the lapped upwardly extending flanges of members of adjacent courses, said return bend on each of said members and the upwardly extending flanges overlapped thereby constituting guide means for the positioning of members of one course relative to an adjacent course and providing weathertight joints between adjacent courses.

6. A trussless roof comprising in combination a plurality of courses extending from one edge to the opposite edge thereof, each course being arched lengthwise thereof upwardly from its ends towards its center and comprising a plurality of sheet metal channeled members, each of said members comprising side flange means connected by a web, said side flange means on opposite sides of each member including a vertically extending flange, said members of each course being disposed in end to end relation with at least portions of the ends of adjacent members in lapping engagement, the joints between the members of each course being non-coincident with the joints between the members of adjacent courses, each of said members being disposed with its vertically extending flanges at its respective sides in lapping engagement with the vertically extending flanges of members of adjacent courses, a bracing member extending between and fastened to the opposite side flange means of each of said members, fastening elements extending through the lapped end portions of adjacent members of each course, and fastening elements extending through the lapped vertically extending flanges of members of adjacent courses.

7. A trussless roof comprising in combination a plurality of courses extending from one edge to the opposite edge thereof, each course being arched lengthwise thereof upwardly from its ends towards its center and comprising a plurality of sheet metal members, each of said members being channel-like in shape and comprising side flange means connected by a web and being positioned with its open side disposed outwardly of the roof, said members of each course being disposed in

end to end relation with at least portions of the ends of adjacent members in lapping engagement and with at least portions of their flange means in lapping engagement with at least portions of the flange means of the members of adjacent courses, the joints between the members of each course being non-coincident with the joints between the members of adjacent courses, fastening elements extending through the lapped end portions of adjacent members of each course, and fastening elements extending through said portions of the flange means of the members of one course at their respective sides and the flange portions of the members of adjacent courses in lapping arrangement therewith.

8. A trussless roof comprising in combination a plurality of courses extending from one edge to the opposite edge thereof, each course being arched lengthwise thereof upwardly from its ends towards its center and comprising a plurality of sheet metal members, each of said members being channel-like in shape and comprising side flange means connected by a web and being positioned with its open side disposed outwardly of the roof, said side flange means on opposite sides of each member comprising a first flange connected to said web and a second flange connected by ledge means with said first flange, said ledge means on opposite sides of each member being adapted to support a panel of insulation therebetween spaced outwardly from the web of the member, said members of each course being disposed in end to end relation with at least portions of the ends of adjacent members in lapping engagement, the joints between the members of each course being non-coincident with the joints between the members of adjacent courses, each of said members being disposed with its said second flanges at its respective sides in lapping engagement with the second flanges of members of adjacent courses, fastening elements extending through the lapped second flanges of members of adjacent courses.

9. A roof member formed of sheet metal bent along longitudinal lines into channel-like shape to provide a central web and side flange means connected thereby, said flange means on opposite sides of the roof member including a side flange extending substantially at right angles to said web with the side flange on one side terminating in a return bend adapted to overlap a side flange of an adjacent member, at least portions of the ends and said flanges of said member being provided with openings therethrough to receive fastening elements for attaching the roof member to adjacent similar roof members.

10. A roof member formed of sheet metal bent along longitudinal lines into channel-like shape to provide a central web and side flange means connected thereby, said flange means on opposite sides of the roof member comprising a first flange connected to said web and a vertical flange joined by connecting flange means with said first flange, said vertical flange on one side of the member terminating in a return bend adapted to lap a vertical side flange of an adjacent roof member, said web and each of said flanges adjacent their ends and said vertical flanges along their lengths being provided with openings therethrough to receive fastening elements for attaching the roof member to adjacent similar roof members.
